UNITED STATES PATENT OFFICE.

JESSE W. WILDERMUTH, OF LANCASTER, OHIO, ASSIGNOR TO THE LIBBEY-OWENS SHEET GLASS COMPANY, OF TOLEDO, OHIO, A CORPORATION OF OHIO.

SHEET-GLASS COOLER.

Application filed October 13, 1924. Serial No. 743,226.

The present invention relates to an improved cooler and has reference to a cooler particularly well-adapted for use in connection with sheet glass drawing apparatus.

5 An important object of the invention is to provide a cooler for use in connection with sheet glass drawing apparatus wherein a continuous circulation of cooling medium is had so that the possibilities of the cooler 10 clogging up and bursting are remote.

A further object of the invention is to provide a cooler having a tortuous passage for a cooling medium whereby the cooler can be associated with the tank wall and the 15 tongue arch of sheet glass drawing apparatus in a manner to prevent deterioration of these members due to the terrific heat to which they are exposed.

A still further object of the invention is 20 to provide a cooler of this nature wherein a continuous flow of water is passed therethrough in a manner to prevent formation of steam pockets and the like which are detrimental to the action of such coolers.

25 Other objects and advantages of the invention will become apparent during the course of the following description.

In the drawings wherein like numerals are employed to designate like parts 30 throughout the same—

Fig. 1 is a longitudinal section through a portion of the apparatus for drawing sheet glass showing the coolers in conjunction with the tank wall and tongue arch,

35 Fig. 2 is an elevation of a cooler adapted for use in connection with the tongue arch of such apparatus,

Fig. 3 is an elevation of the cooler adapted for use on the tank wall,

40 Fig. 4 is a fragmentary sectional view through the tank wall cooler,

Fig. 5 is a fragmentary sectional view of the tongue arch cooler,

45 Fig. 6 is a fragmentary perspective view showing a portion of the cooler before assembly,

Fig. 7 is a fragmentary perspective view showing one form of detail of construction, and

50 Fig. 8 is a section taken substantially on line 8—8 of Fig. 3.

In the drawings wherein for the purposes of illustration is shown the preferred embodiment of the invention, numeral 10 designates a portion of a sheet glass drawing

apparatus and includes a tank 11 having a source of molten glass 12 arranged therein. Ordinarily the glass 12 is heated by means of gas flames. In the type of machine illustrated the flames are played upon the 60 glass, first at one side of the machine and then at the other side. In other words, heating is accomplished by having sets of burners on both sides of the tank 11. During the time for instance that the left hand 65 burners of the furnace are going the exhaust therefrom will pass through the conduits 13 and heat the checker-work 14 so that when the burners at the left-hand side of the furnace are cut off and the burners at the right- 70 hand side placed in operation, the air drawn up through the checker-work 14 will be sufficiently heated to aid combustion of the gases fed through the port 15, thus giving an exceptionally hot flame with a minimum 75 amount of waste. The tongue arch 16 is exposed to very high temperatures, and to prevent disintegration thereof, it is necessary to place a cooler at one end as shown in Fig. 1 to protect the same. Due to the 80 inconvenient location of the cooler at the end of the tongue arch it is desirable to have one that will withstand the terrific heat for a considerable length of time to prevent constant replacement.

85 In addition to the burning away of the tongue arch the walls of tank 11 are gradually decomposed as at 17 until eventually the entire wall is gone. To offset this tendency it is necessary to place coolers on the outside 90 of the wall as shown in Fig. 1 to chill the same.

In order to provide satisfactory coolers it is necessary to have a cooler in which a continuous circulation of a cooling medium can 95 be had. In many types of coolers steam pockets, etc. form therein, thus causing a poor circulation and clogging up of the cooler with resultant blowing up of the same.

100 In the present form of the invention I construct a cooler from a plurality of substantially cylindrical sections 18, which are arranged in substantial parallel relationship. In Figs. 6, 7 and 8, the details of the construction are shown, wherein the ends of the sections 18 are split along a line as at 19 for a substantial distance. The section is then cut at right angles as at 20 approximately half way through the section, after which

the lips 21 are bent up and beveled as at 22. As seen in Figs. 7 and 8 lips of the same ends of adjacent sections are welded together as at 25 to provide a water-tight joint, 5 after which a cap or plate 23 is welded in the ends to close up the sections. The spaces or gaps 27 formed between the inner ends of the lips 21 and the cylindrical sections 18 can be closed by welding the said lips and 10 sections together or if desired, plates or the like 26 can be welded or otherwise suitably secured within the said spaces or gaps.

As shown in Fig. 2 the cooling medium is introduced in one of the outermost sections 15 and flows therealong to its opposite end where it passes down into the adjacent section and so on through the various sections until it passes out through the exhaust. It will be seen that this arrangement of cooler 20 provides a tortuous passage for the cooling medium so that there is a continuous flow. Due to the fact that the sections 18 are formed from substantially cylindrical material, the cooler will be in effect a self-flushing one, thus preventing accumulation of 25 sediment or the like, so that the cooler will at all times be kept free from dirt and steam pockets so that under ordinary conditions the chances for blowing up of the cooler are 30 rather remote.

In order to adapt the cooler to the curvature of the tongue arch 16, it is necessary to curve the same as shown in Fig. 2. In both types of coolers the circulation is identical.

35 In the foregoing it will be seen that a cooler formed in accordance with the present invention will provide a tortuous passage for a cooling medium while at the same time the cooler will be continuously flushed due 40 to the cross-sectional shape of the members from which the cooler is formed.

It is to be understood that the form of the invention herewith shown and described is to be taken as the preferred embodiment 45 of the same, and that various changes in the shape, size and arrangement of parts may be resorted to without departing from the spirit of the invention or the scope of the subjoined claims.

50 Claims:

1. In a combination with a sheet glass apparatus, a cooler comprising a plurality of separate cylindrical members arranged in parallel relationship, each member contacting with its adjacent members, and means connecting one end of each member with an end of one adjacent member, and the opposite end with the other adjacent member to form a tortuous passage for the flow of a 55 cooling medium therethrough.

60 2. In combination with a sheet glass machine, a cooler comprising a plurality of

separate cylindrical sections arranged in parallel relationship, each section contacting with its adjacent sections, means for connecting the sections in a manner to form a tortuous passage for a flow of a cooling medium, the cooler as a unit having but a single inlet and a single outlet. 65

3. A cooler for use in glass apparatus, 70 comprising a plurality of separate cylindrical members arranged in parallel relationship, each member contacting with the adjacent members, one end of each member and the same end of one adjacent member 75 being provided with lips, the lips of said members being directed towards and secured to one another, and means for closing the ends of said members.

4. A cooler for use in glass apparatus, 80 comprising a plurality of separate cylindrical members arranged in parallel relationship, each member contacting with the adjacent members, one end of each member and the same end of one adjacent member 85 being directed towards and secured to one another, means for closing the ends of said members, and means for closing the spaces between the inner ends of said lips and members. 90

5. A cooler for use in glass apparatus, comprising a plurality of separate cylindrical members arranged in parallel relationship, each member contacting with the adjacent members, one end of each member 95 and the same end of the adjacent member at one side thereof being provided with lips, the lips of said members being directed towards and secured to one another, the opposite end of each member being provided 100 with similar lips directed in the opposite direction to the lips at the other end thereof and secured to corresponding lips formed at the same end of the adjacent member at the opposite side thereof, and means for closing 105 the outer ends of said members.

6. A cooler for use in glass apparatus, comprising a plurality of separate cylindrical members arranged in parallel relationship, each member contacting with the 110 adjacent members, one end of each member and the same end of one adjacent member being split longitudinally and cut transversely at the inner end of the split to provide a pair of lips, the lips of said adjacent members being directed towards and secured to one another, a single closure secured to the outer ends of said lips, and means for closing the spaces between the inner ends 115 of said lips and said members. 120

Signed at Lancaster, in the county of Fairfield and State of Ohio, this 9th day of October, 1924.
